UNITED STATES PATENT OFFICE.

WALDEN EDDY, OF GREENWICH, NEW YORK.

SHOVEL-PLOW.

SPECIFICATION forming part of Letters Patent No. 289,238, dated November 27, 1883.

Application filed April 18, 1883. (No model.)

To all whom it may concern:

Be it known that I, WALDEN EDDY, of Greenwich, in the county of Washington and State of New York, have invented certain new and useful Improvements in Shovel-Plows, of which the following is a full, clear, and exact description.

This invention relates to winged shovel-plows provided with subsoil attachments or spring-teeth arranged to follow in the wake of the shovel-plow, on opposite sides of it, and so as to work at a lower depth than the point of the plow, for loosening the ground laterally beyond the center of the row in which the shovel-plow works, and nearer to the growing crop.

The invention mainly consists in a novel combination, with the point, wings, and mold-board of the plow, which is preferably made with a cast beam and standard, of the subsoil attachments or teeth, and means for securing and adjusting the same, and every facility is afforded for adjusting said teeth to work closer or farther apart, and shallower or deeper, also for their detachment when not needed.

Reference is to be had to the accompanying drawings, forming part of this specification, in which similar letters of reference indicate corresponding parts in all the figures.

30 Figure 1 represents a view in perspective of a plow embodying my invention; Fig. 2, an inverted plan, upon a larger scale, of said plow in part. Fig. 3 is a face view of the forward portion of one of the subsoiling attachments.

35 A A' in the drawings indicate the beam and standard of the plow, made of cast metal in one piece.

B is the shovel-point, C the mold-board, and D D the wings, of the plow.

40 E E are the handles.

G G are the subsoil attachments or spring-teeth, arranged to project from opposite sides of the winged shovel-plow, and so as to work at a lower depth than the point of it, for the 45 purposes hereinbefore mentioned. These teeth or attachments G G are formed of flat bars bent and arranged to project laterally and backwardly in diverging directions from the under side of the mold-board C, and are curved 50 downwardly, and suitably twisted or bent at their rear ends, as at b, to bring their points in proper subsoiling position. The forward portions of these attachments G G, which rest

on or against the under side of the mold-board C, are each made with elongated slots d d' in them, the one in rear of the other. These slots should be suitably shaped to provide for every necessary adjustment of the subsoiling attachments—that is, to provide for said attachment being widened or contracted, and to 55 run deeper or shallower at their points. For these purposes the rear slot, d, may be made of T shape, and the forward one, d', be of an obtuse angular construction, as shown in Figs. 2 and 3. The bolts e e, which pass through 60 said slots to secure the adjustable attachments G G, are the same bolts as are used to hold the point B and wings D D to the mold-board C, and pass not only through the mold-board and shovel-point and wings, but also through the 65 slotted portions of the subsoiling attachments. In this way the construction is simplified, as the same sets of bolts answer a double purpose, and both the mold-boards and wings are 70 strengthened by the subsoiling attachments G G passing under them. By slackening the bolts e e said subsoiling attachments may 75 readily be adjusted as required, and the bolts afterward be tightened up again; or they may be easily removed from the plow when 80 not needed.

Having thus described my invention, what I claim as new, and desire to secure by Letters Patent, is—

1. The combination, with the point B of the 85 shovel-plow, its wings D D, and mold-board C, of the adjustable subsoiling attachments or teeth G G, and the bolts e e, arranged to pass through slots in said attachments and through the point, wings, and mold-board of the plow, 90 substantially as specified.

2. The subsoiling attachments or teeth G G, of flattened bar construction, bent to diverge 95 backwardly from under the mold-board of the plow, and curved downwardly and forwardly at their rear ends, also provided with slots d d' at or in their forward portions, in combination with the mold-board C, the cast beam and standard A A', the shovel-point B, the wings D D, and the bolts e e, essentially as 100 shown and described.

WALDEN EDDY.
